United States Patent Office

Des. 219,284
Patented Nov. 24, 1970

219,284

BALL TOY

Philip J. Hunt, 217 E. Front, Adrian, Mich. 49221

Filed Jan. 22, 1970, Ser. No. 21,035

Term of patent 14 years

Int. Cl. D21—03

U.S. Cl. D34—15

FIG. 1

FIG. 2

FIG. 3

FIG. 1 is a perspective view of a ball toy showing my new design;

FIG. 2 is a plan view of the infant's toy; and

FIG. 3 is a side view of the infant's toy.

I claim:

The ornamental design for a ball toy, as shown.
